(57) **CLAIM**

The ornamental design for a belt-mounted tool carrier, as
shown and described.

DESCRIPTION

FIG. 1 is an isometric view of a belt-mounted tool carrier,
showing our new design, taken from the upper right front;
FIG. 2 is a rear elevational view thereof;
FIG. 3 is a right side elevational view thereof, the left side
elevational view thereof being a mirror image of this view;
FIG. 4 is a front elevational view of the carrier shown in
FIGS. 1-3;
FIG. 5 is a top plan view thereof; and,
FIG. 6 is a bottom plan view thereof.
